CLAIM

The ornamental design for a gaming simulator seat, as shown and described.

DESCRIPTION

FIG. 1 is an upper front perspective view of a gaming simulator seat showing my new design;

FIG. 2 is an upper rear perspective view thereof;

FIG. 3 is a rear view thereof;

FIG. 4 is a front view thereof;

FIG. 5 is a right view of thereof;

FIG. 6 is a left view thereof;

FIG. 7 is a bottom view thereof;

FIG. 8 is a top view thereof;

FIG. 9 is a lower front perspective view thereof; and,

FIG. 10 is a lower rear perspective view thereof.

1 Claim, 10 Drawing Sheets(56)
